(57) **CLAIM**

The ornamental design for an optical connector with shutter, as shown and described.

DESCRIPTION

FIG. 1 is a front view of an optical connector with shutter showing our new design;

FIG. 2 is a rear view thereof;

FIG. 3 is a right side view thereof;

FIG. 4 is a left side view thereof;

FIG. 5 is a plan view thereof;

FIG. 6 is a bottom view thereof;

FIG. 7 is a front perspective view thereof;

FIG. 8 is a rear perspective view thereof;

FIG. 9 is a cross-sectional view thereof, taken along the line 9—9, in FIG. 1;

FIG. 10 is a cross-sectional view thereof, taken along the line 10—10, in FIG. 1;

FIG. 11 is a cross-sectional view thereof, taken along the line 11—11, in FIG. 1, in use condition; and,

FIG. 12 is a cross-sectional view thereof, taken along the line 11—11, in FIG. 1, with lower shutter is inclined.

The broken line shown the environment is for illustrative purposes only and form no part of the claimed design.
